CLAIM

The ornamental design for a resuscitator for newborn pigs, as shown and described.

DESCRIPTION

FIG. 1 is an isometric view of a resuscitator for newborn pigs or the like showing my new design;
FIG. 2 is a side elevational view thereof;
FIG. 3 is a left end elevational view thereof;
FIG. 4 is a right end elevational view thereof.
The appearance of the elevation view, the design as shown in FIG. 2, is the same when viewed from any angle about the horizontal axis thereof.
